ELECTRIC SHAVER

Maximilian T. Edwards, 5450 University Blvd.,
Vancouver, British Columbia, Canada

Filed Nov. 13, 1962, Ser. No. 72,488

Term of patent 3½ years

(Cl. D22—3)

FIG. 1.

FIG. 2.

FIG. 3.

FIG. 4.

FIGURE 1 is a front elevational view of an electric shaver showing my new design;

FIGURE 2 is a side elevational view thereof;

FIGURE 3 is a top plan view; and

FIGURE 4 is a bottom plan view thereof.

I claim:

The ornamental design for an electric shaver, as shown.
